ATTORNEY.

UNITED STATES PATENT OFFICE.

JOSEPH A. DUEIRST, OF PHILADELPHIA, PENNSYLVANIA.

ZITHER SUPPORT AND SOUNDING DEVICE.

SPECIFICATION forming part of Letters Patent No. 694,094, dated February 25, 1902.

Application filed January 30, 1901. Serial No. 45,291. (No model.)

To all whom it may concern:

Be it known that I, JOSEPH A. DUEIRST, a citizen of the United States, residing at Philadelphia, in the county of Philadelphia and 5 State of Pennsylvania, have invented certain new and useful Improvements in Zither Supports and Sounding Devices, of which the following is a specification.

My invention relates to a zither support and 10 sounding device, and has for its object to provide a conveniently-adjusted support for the top of the zither to thereby prevent the usual sagging of the top, with its consequent effect of varying the tension and pitch-note 15 of the strings or the more serious effect of a total collapse of the top under the tension of the strings.

The object of my invention is to provide an 20 improved zither support and sounding device consisting of a bottom plate having a screw mounted therein which is provided with a shoulder adapted to support a top plate and a square portion upon its free end by which the device may be adjusted.

25 Another object is to provide a support of this character that by its bearing upon the upper side of the bottom of the zither and the under side of the top of the same, with the screw connecting the bearings or supports and the 30 device located at or contiguous to the sound-hole, the sound effect shall be greatly improved.

The invention consists in the parts and 35 combination of parts hereinafter described, illustrated, and pointed out in the claim.

In the drawings, Figure 1 is a top plan view 40 of a zither, which may be of any preferred form of construction, the device being shown as applied thereto in the feature of the top support shown as extending transversely of the sound-hole and bearing against the under side of the top. Fig. 2 is a side elevation showing the device in position within the body of the zither, portions of the latter being 45 shown in section. Fig. 3 is a sectional detail view showing a preferred form of construction.

1 designates the zither, with the usual sound-hole 2 formed in the top 3, the bottom being 50 designated by the numeral 4.

The support comprises a base-plate 5, having a central screw-threaded boss 6, a top plate 7 of a length to span the sound-hole 2 and bear against the marginal side thereof, with a central orifice 8, and preferably a bearing 9 upon its under side. 55

10 designates a screw, preferably with a left-hand thread, the lower end of which screws into the lower plate and is provided with a shoulder 11 to bear upon the upper plate at the 60 bearing 9 and with a squared end 12, upon which the string-wrench may be adjusted to revolve the screw and cause the plate 7 to bear with any desired degree of pressure upon the under side of the top 3. 65

The effect of the support is to fully sustain the broad top of the zither from sinking from its normal relation with the bottom 4, thereby maintaining a determinate tension upon the strings and also preventing a collapse of 70 the top, as often occurs. A further effect is to, by the connection with the bottom and top by a determinate pressure, greatly increase the musical tone of the instrument—that is to say, render the modifications of tone controllable. 75

While I have described my invention as particularly applicable to a zither, it is adaptable to different forms of stringed instruments, and I wish it to be so understood in 80 the interpretation of the claim.

What I claim is—

In a zither support and sounding device, the combination of a bottom plate having a screw-threaded orifice, a screw mounted in the said 85 threaded orifice, a shoulder upon the said screw, a top plate having a central orifice, the said top plate supported by the said shoulder, and a square portion upon the free end of the said screw, projecting up through the orifice 90 in the said top plate, substantially as shown and for the purpose set forth.

In testimony whereof I affix my signature in presence of two witnesses.

JOSEPH A. DUEIRST.
